COMBINED DENTIFRICE DISPENSER AND TOOTHBRUSH HOLDER

Robert S. Hamilton, 5639 N. Milbrook, Fresno, Calif.

Filed June 10, 1963, Ser. No. 75,294

Term of patent 14 years

(Cl. D4—3)

FIG. 1.

FIG. 2.

FIG. 3.

FIG. 4.

FIG. 5.

FIG. 1 is a front elevation of a combined dentifrice dispenser and toothbrush holder showing my new design.

FIG. 2 is a rear elevation thereof.

FIG. 3 is a side elevation thereof.

FIG. 4 is a top plan view thereof.

FIG. 5 is a bottom plan view thereof.

The dominant features of my design reside in the portions shown in full lines.

I claim:

The ornamental design for a combined dentifrice dispenser and toothbrush holder, as shown and described.
